CLAIM

We claim the ornamental design for a clothing care machine, as shown and described.

DESCRIPTION

FIG. 1 is a perspective view of a clothing care machine showing a new design;

FIG. 2 is a front view thereof;

FIG. 3 is a rear view thereof;

FIG. 4 is a left-side elevation view thereof;

FIG. 5 is a right-side elevation view thereof;

FIG. 6 is a top plan view thereof;

FIG. 7 is a bottom plan view thereof; and,

FIG. 8 is a partial enlarged detail view of the portion designated **8** in FIG. 1.

The dot-dot-dash broken lines shown in FIGS. 1 and 8 indicate cutoff boundaries for the enlarged detailed portion views and form no part of the claimed design. The broken lines shown in the drawings illustrate portions of the clothing care machine that form no part thereof.
